MAGNET-RAIL FOR ELECTRICAL MUSICAL INSTRUMENTS.

1,209,214.

Specification of Letters Patent.

Patented Dec. 19, 1916.

Application filed January 4, 1913. Serial No. 740,201.

To all whom it may concern:

Be it known that we, MELVIN L. SEVERY, of Arlington Heights, in the county of Middlesex and Commonwealth of Massachusetts, and GEORGE B. SINCLAIR, of Georgetown, in the county of Sagadahoc and State of Maine, both citizens of the United States, have invented certain new and useful Improvements in Magnet-Rails for Electrical Musical Instruments, of which the following is a full and exact description.

This invention relates to musical instruments comprising tuned electromagnetically attractive sonorous bodies vibrated by means of closely disposed electromagnets having properly timed electric pulsations delivered thereto; and this invention has for its objects the construction of improved means for supporting said electromagnets; and to improvements in the electromagnets themselves.

Referring to the drawings forming part of this specification, Figure 1 is an elevation of a rail for the support of the electromagnets embodying one form of the invention. Fig. 2 is a cross section of the same on the line X—X in Fig. 1. Fig. 3 is a cross section on the line Z—Z in Fig. 1. Fig. 4 is a top view of the magnet rail and of magnets carried thereby. Fig. 5 is a sectional detail view of one of the spherical nuts used in the rail. Fig. 6 is a perspective view of a musical instrument showing the position of the magnet rail and connected parts. Fig. 7 is a face view of a portion of an improved form of the magnet rail. Fig. 8 is a perspective view of the same. Fig. 9 is a cross section of the rail. Fig. 10 is a rear elevation of part of the rail. Fig. 11 is a front elevation of a part of the same. Fig. 12 is a side view of one of the base electromagnets. Fig. 13 is a side view of one of the treble electromagnets.

The sonorous bodies illustrated in the drawings are strings 1 of the usual piano type, vibrated by means of electromagnets supported by a magnet rail 3 and receiving current from a source 4, through make-and-break devices comprising brushes 5 and toothed disks or rings 6, and connections

consisting of a common lead wire 8 between said source and all the magnets, a wire 9 from each magnet to a brush 5, and a brush 10 and wire 11 between said source and members 6. The circuit through each wire 55 9 being controlled by a pair of contacts 7, 7^a, by means of keys, or in any other manner.

In Letters Patent No. 1,097,052 granted to us under date May 19, 1914, we have shown and described a magnet rail comprising two sections pivotally connected at their proximate ends, and pivotally supported at their remote ends upon brackets rendered capable of adjustment forward and backward, and having means for securing 60 the brackets in their adjusted positions. The proximate ends of the rail sections were, under the patented construction, connected with a pedal or lever whereby said sections and their magnets might be moved 65 toward and from the strings or other tuned sonorous bodies with which they were associated. By the patented construction provision was made for adjusting the entire magnet rail bodily forward and backward 70 and for adjusting said rail bodily by a movement about the pivotal support of either end, the end supports in each case being rigidly fixed in their adjusted positions. Finally, the meeting ends of the rail 75 sections were drawn toward the strings or other sonorous bodies by a spring, and were movable from the strings through the pedal and intermediate connections.

Under the present construction provision 85 is made not only for moving the magnet-rail bodily toward and from the strings or other sonorous bodies, or moving either end forward or backward and clamping the ends in their adjusted positions, but also for tipping the rail transversely so as to bring the poles of the magnets into planes parallel with the strings or sonorous bodies; for adjusting the individual magnets axially and tipping them in any desired direction relatively to the supporting rail, so that their extremities may be accurately placed in proper relation to the strings with which they are associated; and finally, for moving 90 the meeting ends of the rail sections toward 95 100

and from the strings or sonorous bodies and locking or securing them in adjusted position. By our improved construction we secure not only the several adjustments afforded by the patented construction, but we also provide for more perfect adjustment of the magnets individually and collectively.

As in the patented structure, so here, the upper treble magnets are placed nearest 10 their associated strings, the low bass magnets slightly farther from their strings, and the intermediate magnets at a greater distance from their strings than either the upper treble or low bass magnets.

15 As shown in Fig. 1, the two sections 12 and 13 of the rail are hinged together by means of a metal strap 14 fixed to the end of section 12 and having ears 16 formed with slots or notches 15 (Fig. 4) through which 20 are inserted pins 17 into the section 13. Immediately above said hinge is a finger 18 adapted to engage the annular groove 21 of a screw 20 (Figs. 1 and 3) in a manner to support such hinged portion of the rail, said 25 screw turning in suitable parts of the frame 23. By turning said screw, the intermediate portion of the rail is moved toward or from the strings, the parts more removed from the hinge being shifted to lesser extents.

30 The extreme bass end of the section 12 is adjustably supported by means of a bar 24 fastened thereto (Figs. 1 and 2), through the midlength of which bar passes a screw 25 tapped into a spherical nut 26 confined 35 in a block 27 (Figs. 2 and 5), the head of said screw being formed with a groove 29 engaged by a finger 30 fixed to the string plate 28. The rotation of said screw serves to pull or push the rail thereat in accordance 40 with the direction of such rotation. Tapped through said plate 28 above and below said rail are screws 31 abutting against the ends of said bar 24, and adapted by their opposite turning to angularly adjust 45 just the rail on its longitudinal axis as a center. The three screws acting together permit of the bodily adjustment toward or from the strings.

50 For the treble end of the rail section 13, a single screw 32 may be employed, coacting with a spherical nut 33 (Figs. 1, 4) and in all other ways controlled like the screw 25 above described. This spherical nut allows the rotative adjustment of the rail. In this 55 way the magnet rail is enabled to be adjusted in all ways necessary for the presentation of the magnets 2 to their strings at accurately determined distances therefrom.

60 The magnet rail thus far described is of wood, but we prefer to use metal as far less liable to be affected by hygrometric conditions, and warping, swelling and splitting. When of metal, the rail sections may be 65 comparatively thin, as shown in Figs. 8 and 9, and are stiffened by flanges 34. On the

face of each section are several rows of lugs 35 between which slidably fit the yokes 36 of the electromagnets 2, in order to insure against their shifting either laterally or angularly. For the individual adjustment 70 of each magnet, four screws are provided, the central one 37 of which is tapped into said part 36 but turns freely in the rail, while the other screws 39 are tapped through 75 the rail and set against the surface of said part. These four screws allow of a slight but sufficient angular adjustment in any direction, and also of a bodily movement of the magnet toward and from its string, but at the same time confining the magnet 80 firmly in position. These adjustments are of exceedingly great value, for the reason that if one pole of a magnet is nearer its string than the other, the nearer pole may be struck by the string and cause a highly 85 objectionable metallic twanging. Or, if the nearer pole is sufficiently removed to be out of danger of such striking, the other pole will be so far away as to be practically 90 without effect upon the string.

90 For perfect work, both poles of every magnet must be equally removed from its string, and yet as close thereto as possible, in order to give a maximum attractive effect, while being just beyond possible contact therewith. This will be realized more fully when it is recalled that the attraction of a magnet for its armature varies in inverse proportion to the squares of its distances therefrom.

95 Our preferred form of magnet rail we adjust in a somewhat different way from that above described, and have the two sections thereof not hinged together, but entirely independent of each other. Here a suitably supported bracket 40 is provided with two sets of three screws, one set for one rail section, and the other set for the other section. See Fig. 11. In each of said sets, the intermediate screw 41 sets against the rail 100 surface, and the outermost screws 42 are tapped through the same, the effect being precisely like that of the screws 25 and 31 above described, since as we have found, the adjustment required is so slight as not to 105 require the spherical nut 26. On the other hand, the cost is considerably less for the last-described construction.

110 A similar bracket 44 (Fig. 8), with like screws 41, 42, is provided for each of the 115 other ends of the rail-sections, (Figs. 7 and 8) so that each section can be adjusted both angularly and bodily to present the magnets as a whole at the proper distances from the strings; while the above-described individual adjustment of the electromagnets 120 cares for the finer inaccuracies of position.

125 The main object of the lugs 35 is to keep the electromagnets from turning on the screws 37 in a plane parallel with the face 130

of the rail, and to hold them plumb and true.

We have discovered that it is desirable to vary the lengths of the yokes 36 of the electromagnets, the bass magnets having 5 said members 36 quite long, as in Fig. 12, the treble magnets having them quite short, as shown in Fig. 13, and the intermediate parts 36 being of medium length, as in Fig. 9. The purposes of such variations are two-fold: first, to avoid the leakage across the poles of each magnet when the poles are near together. It is necessary to have the poles of the upper electromagnets 10 close together in order that both poles may be close as possible to the proper striking points of the strings, since the shortness of the upper treble strings correspondingly limits the space allowable for the striking 15 points. As the lengths of the strings increase, the distances between the magnet- poles can be increased, and the magnetic- leakage reduced to a minimum. The sec- 20 ond purpose accomplished by the increase in length of the yokes 36 is to materially aug- ment the amount of iron in the magnets and thus to increase the strength of the magnets and with it the loudness of the notes pro- 25 duced, without change in current-strength.

This lengthening of the yokes is more effi- 30 cient and economical to do than to increase the diameters of the cores 2^a, although this also is done, as shown in Figs. 9, 12 and 13.

The dimensions of the magnets may vary 35 considerably without destroying the effi- ciency of the instrument, but our experience has caused us to adopt in practice $\frac{1}{4}$ of an inch as the preferred diameter of cores for magnets of the extreme treble strings, with 40 a spacing of $\frac{13}{16}$ of an inch between core axes; and a diameter of $\frac{3}{8}$ of an inch for the cores of the magnets of the lowest bass strings, with a spacing of $1\frac{5}{16}$ inches between the 45 axes of said cores. The magnet yokes are, in practice, made of Norway iron $\frac{1}{4}$ of an inch in thickness, $\frac{3}{4}$ of an inch in width, and of a length proportionate to the separation of the cores, it being material only 50 that there be sufficient iron in the yokes, or in other words, a surplus causing no ill effects.

The magnet windings we find convenient and suitable are of Nos. 25 and 26 enameled or cotton-covered copper wire, wound to 55 offer 20 ohms resistance in the case of the extreme lower bass string magnets, and 5 ohms resistance in the case of the extreme treble string magnets.

Theoretically, dimensions and spacing of 60 cores, and resistance offered by the windings, should vary between the selected limits or extremes, progressively and uniformly from magnet to magnet throughout the series. This, however, is commercially impractical, and the following have been adopted 65

as the extremes and intermediate variations which we have found best to meet or balance theoretical and commercial considerations:

Notes.	Resistance.	Core diameters.	Separation of core axes.	70
1-25.....	20 ohms	$\frac{3}{4}$ inch	$1\frac{5}{16}$ inches.	
26-31.....	12 ohms	$\frac{3}{4}$ inch	1 inch.	
32-40.....	9 ohms	$\frac{3}{4}$ inch	1 inch.	
41-68.....	5 ohms	$\frac{1}{2}$ inch	1 inch.	
69-73.....	5 ohms	$\frac{1}{2}$ inch	$1\frac{1}{16}$ inch.	75

What we claim as our invention and for which we desire Letters Patent is as follows, to wit:—

1. A musical instrument comprising magnetically attractive sonorous bodies and electric means including electromagnets for the vibration of said sonorous bodies; a magnet-rail for the support of said electromagnets; means for adjusting said rail bodily toward and from said sonorous bodies and for angularly adjusting the rail about its longitudinal axis; and means for rigidly securing said rail in adjusted position. 80

2. A musical instrument comprising magnetically attractive sonorous bodies and electric means including electromagnets for the vibration of said sonorous bodies; a magnet rail for the support of said electromagnets, said magnet-rail being in a plurality of sections adjustable at their proximate ends relative to said sonorous bodies; and means for rigidly securing said proximate ends in adjusted position.

3. A musical instrument comprising magnetically attractive sonorous bodies and electric means including electromagnets for the vibration of said sonorous bodies; a magnet-rail for the support of said electromagnets, said rail being in two sections adjustable at their proximate ends relative to said sonorous bodies; and means for rigidly securing said proximate ends in adjusted position.

4. A musical instrument comprising magnetically attractive sonorous bodies and electric means including electromagnets for the vibration of said sonorous bodies; a magnet-rail for the support of said electromagnets, said rail being in two sections; means for bodily adjusting the rail sections toward and from said sonorous bodies; means for angularly adjusting said rail sections about their longitudinal axes; and means for rigidly securing said sections in their adjusted positions.

5. A musical instrument comprising magnetically attractive sonorous bodies and electric means including electromagnets for the vibration of said bodies; a magnet-rail for the support of said electromagnets; fixed brackets at the ends of said rail for supporting the same; and means connected with said brackets for adjusting said rail bodily toward and from the brackets and angularly

- 4
- with reference thereto, and serving also to secure the rail in its adjusted position.
6. A musical instrument comprising magnetically attractive sonorous bodies and electric means including electromagnets for the vibration of said bodies, a magnet rail for the support of said electromagnets, suitably supported brackets, and three screws for each bracket adapted for a push and pull engagement with the rail.
7. A musical instrument comprising magnetically attractive sonorous bodies and electric means including electromagnets for the vibration of said bodies, a magnet rail for the support of said electromagnets, suitable supporting means, and three screws at each end of said rail held by said supporting means, said three screws being in a substantially vertical line, the intermediate screw pushing against the rail and the outermost screws being tapped into and pulling the rail.
8. A musical instrument comprising magnetically attractive sonorous bodies and electric means including electromagnets for the vibration of said bodies, a magnet rail for the support of said electromagnets, said magnet rail being in sections, brackets suitably supported at the ends of said sections, and three screws engaging each end of said sections and held by said brackets.
9. A musical instrument comprising magnetically attractive sonorous bodies and electric means including electromagnets for the vibration of said sonorous bodies; a magnet rail for the support of said electromagnets, comprising independently adjustable rail sections; means for securing said sections in adjusted positions; and means for independently and adjustably securing said electromagnets to said rail; whereby each magnet may be accurately positioned with reference to its associated sonorous body, and the groups of magnets carried by the rail sections may be bodily adjusted toward and from said sonorous bodies.
10. A musical instrument comprising magnetically attractive sonorous bodies and electric means including electromagnets for the vibration of said sonorous bodies; a magnet-rail for the support of said electromagnets; and means for adjustably securing said electromagnets to said rail, said means consisting of a plurality of sets of screws, each set comprising one screw connecting the magnet-yoke with the rail and other screws bearing against and serving to angularly adjust and hold the magnet-yoke in adjusted position.
11. A musical instrument comprising a magnet-rail; a series of electromagnets carried by said rail; tuned sonorous bodies located in attractive relation to and serving as armatures for said electromagnets; means for adjusting the electromagnets toward and from said rail to vary their relation to the tuned sonorous bodies; and guiding lugs for said electromagnets serving to prevent lateral play or movement thereof during adjustment toward and from the rail.
12. A magnet rail for electric musical instruments having rows of lugs upon its outer face, in combination with electromagnets fitting between said lugs, and screws for adjusting the position of each electromagnet toward and from the magnet rail.
13. A magnet rail for electric musical instruments having a plurality of longitudinally disposed rows of lugs upon its outer face, in combination with electromagnets having yokes slideable between said lugs, and screws adapted both to push and pull said electromagnets relative to the rail.
14. A magnet rail for electric musical instruments having a plurality of longitudinally disposed rows of lugs upon its outer face, in combination with electromagnets having yokes slideable between said lugs, a plurality of screws turning in the rail for each yoke adapted to push the latter away from the rail, and a centrally disposed screw for each yoke adapted to draw the latter toward the rail.
15. A musical instrument comprising magnetically attractive sonorous bodies, electric means including electromagnets for vibrating said bodies, and a magnet rail for supporting said electromagnets, said rail being in a plurality of sections each adapted both for angular and bodily adjustment relative to the said bodies, and each of said electromagnets having means for its individual angular and bodily adjustment relative to said bodies.
16. A musical instrument comprising magnetically attractive sonorous bodies of widely different pitches, and electric means including electromagnets for the vibration of said bodies, said electromagnets being provided with different amounts of iron, the amounts being greater for the magnets associated with sonorous bodies of lower pitches than for the magnets associated with the sonorous bodies of higher pitches, substantially as set forth.
17. A musical instrument comprising magnetically attractive sonorous bodies of widely different pitches, and electric means including electromagnets for the vibration of said bodies, the electromagnets associated with bodies of lower pitches having longer yokes than the electromagnets associated with sonorous bodies of higher pitches, substantially as described.
18. In an electric musical instrument, the combination with magnetically attractive strings, electromagnets for their actuation, and means for delivering electric pulsations to said electromagnets, of a magnet rail for supporting said electromagnets, a fixed

plate, a ball-and-socket nut at each end of said rail, screws projecting from said plate against parts rigid with said rail above and below one of the nuts.

5 19. The combination with a plurality of electromagnets, of a magnet rail for supporting said electromagnets, a fixed plate, a ball-and-socket nut at each end of said rail, screws projecting from said plate into said 10 nuts, and set screws projecting from the plate against parts rigid with the rail above and below one of said nuts, said rail being jointed at an intermediate point and provided with hinging means thereat consist-

ing of a terminally slotted fork and pins 15 entering the slots, and supporting and adjusting means consisting of a screw projecting from and turning in said plate, and an arm rising from the rail at such joint in engagement with the screw.

20 In testimony that we claim the foregoing invention, we have hereunto set our hands this 10th day of December, 1912.
